US0D1109121S

(12) **United States Design Patent** (10) Patent No.: **US D1,109,121 S**
(45) Date of Patent: ** Jan. 13, 2026

(54) **DATA PROCESSING DEVICE**

(71) Applicant: **NEXTVPU (SHANGHAI) CO., LTD.**,
Shanghai (CN)

(72) Inventors: **Di Peng**, Shanghai (CN); **Yin Tang**,
Shanghai (CN); **Xinpeng Feng**,
Shanghai (CN); **Ji Zhou**, Shanghai
(CN)

(**) Term: **15 Years**

(21) Appl. No.: **35/523,171**

(22) Filed: **Nov. 1, 2024**

(80) **Hague Agreement Data**

Int. Filing Date: **Nov. 1, 2024**

Int. Reg. No.: **DM/242225**

Int. Reg. Date: **Nov. 1, 2024**

Int. Reg. Pub. Date: **Dec. 6, 2024**

CLAIM

The ornamental design for a data processing device as shown and described.

DESCRIPTION

1. Data processing device

1.1 : Perspective

1.2 : Perspective

1.3 : Front

1.4 : Back

1.5 : Left

1.6 : Right

1.7 : Top

1.8 : Bottom

The dash-dash broken lines shown in the figures depict portions of the data processing device that form no part of the claimed design.
